UNITED STATES PATENT OFFICE.

SYLVESTER CLARK LANEY, OF PITTSBURG, PENNSYLVANIA.

DESIGN FOR A RAILROAD-RAIL.

SPECIFICATION forming part of Design No. 31,249, dated July 18, 1899.

Application filed June 20, 1899. Serial No. 721,248. Term of patent 14 years.

To all whom it may concern:

Be it known that I, SYLVESTER CLARK LANEY, a citizen of the United States of America, residing at Pittsburg, in the county of Allegheny and State of Pennsylvania, have invented a certain new and useful Design in Railroad-Rails, of which the following is a specification, reference being had therein to the accompanying drawing.

- o This invention relates to certain new and ornamental designs in railroad-rails.
- o The invention has for its object to design a rail that will be highly ornamental in its appearance.
- o Briefly described, the design consists of a forward extending V-shaped portion and a cut-away V-shaped portion in the rear end of the rail.

In describing the invention in detail the drawing represents a perspective view of my new and ornamental rail.

Referring to the drawing by reference-numerals, 1 indicates the rail proper, 2 the forward V-shaped portion thereof, and 3 the rear V-shaped cut-away portion.

Having fully described my invention, what I claim as new, and desire to secure by Letters Patent, is—

The design of a railroad-rail, substantially as herein shown and described.

In testimony whereof I affix my signature in the presence of two witnesses.

SYLVESTER CLARK LANEY.

Witnesses:

JOHN NOLAND,
JOHN C. LIVINGSTON.
